MERCHANDISE DISPLAY RACK

Vincent L. Crisafi, Saratoga, Calif.

Application May 24, 1956, Serial No. 41,631

Term of patent 14 years

(Cl. D80—9)

14
71

Fig-1-

Figure 1 is a perspective view taken from the front and one side of the merchandise display rack, embodying my new design; and

The rear of the merchandise display rack is substantially plain.

I claim:

The ornamental design for a merchandise display rack, as shown and described.
